John W. Sharley.
Attorney

UNITED STATES PATENT OFFICE.

WALTER C. SHEPPARD, OF BALTIMORE, MARYLAND.

WRENCH.

1,419,525.

Specification of Letters Patent. Patented June 13, 1922.

Application filed January 13, 1922. Serial No. 529,000.

To all whom it may concern:

Be it known that I, WALTER C. SHEPPARD, a citizen of the United States, residing at Baltimore, in the State of Maryland, have 5 invented certain new and useful Improvements in Wrenches; and I do hereby declare the following to be a full, clear, and exact description of the invention, such as will enable others skilled in the art to which it 10 appertains to make and use the same.

My invention relates to wrenches.

Among the objects of my invention are: * To produce a wrench having an adjustable jaw which can be readily changed in position and locked so that it will operate practically as a solid wrench without danger of the adjustable jaw moving.

To produce a wrench which is simple and capable of manufacture at a small cost.

20 In carrying out my invention I make use of the instrumentalities illustrated in the accompanying drawing, in which:—

Figure 1 is a side view of one of my improved wrenches.

25 Fig. 2 is a view of the wrench shown in Fig. 1 looking in the direction of the arrow 2 in said figure.

Fig. 3 is a partial section along the line 3—3 in Fig. 2 looking in the direction of 30 the arrows.

In the drawings:—

5 represents a lever provided with a wrench jaw 6 and having a rack 7 formed upon the lever 5, the teeth of said rack being angularly disposed with reference to the sides of said lever in order to mesh with the adjusting worm 8.

The movable jaw 9 is slidably mounted upon the lever portion 5 and is provided 40 with bearings in which are revolubly mounted the ends of the screw 10. The screw 10 is screwed tightly into a threaded hole in the worm 8 and its ends serve as pintles for said worm.

45 A locking screw 11 is threaded in a hole in the jaw 9 and is provided with a conoidal point 12 adapted to contact with the rounded end 13 of the screw 10 for a purpose herein-after explained.

50 The spring 14 is secured at one end to the jaw 9 by the screw 15 and its other end embraces the threaded portion of the locking screw 11 and has frictional contact with the underside of the head thereof.

The operation of my improved wrench is 55 as follows:—

The screw 11 is to be turned until the point 12 is out of contact with the end 13. The worm 8 can then be turned in either direction in order to adjust the jaw 9 to the 60 proper distance from the jaw 6 and the locking screw 11 is then to be turned until the point 12 comes in contact with the end 13.

By screwing the screw 11 in, the point 12 will force the end 13 towards the rack 7 until 65 the worm 8 is in firm contact with said rack, thus not only preventing revolution of the worm 8 but taking up any lost motion between said worm and the rack which might prevent a rigid adjustment of the jaw 9 with 70 reference to the lever 5.

It is to be understood that the bearing for the ends of screw 10 are sufficiently loose to permit of a sufficient motion of the worm 8 toward the rack 7 to eliminate lost motion 75 between said parts.

It is also to be noted that the spring 14 produces sufficient friction upon the locking screw 11 to prevent inadvertent movement of 80 the latter.

While I have shown one preferred embodiment of my invention it is to be understood that I do not desire to be limited to the exact structure therein shown, for many changes may be made therein without departing from the spirit of my invention. 85

I claim:—

1. The combination with a lever, a rack and a wrench jaw fixed on said lever and a sliding jaw on said lever, of a worm engaging said rack and having a pintle revolubly mounted in said sliding jaw and a set screw engaging said pintle to prevent the revolution of said worm. 90

2. The combination with a lever, a rack and a wrench jaw fixed on said lever and a sliding jaw on said lever, of a worm engaging said rack and having a pintle revolubly mounted in a loose bearing in said sliding jaw and a set screw engaging said pintle 100 to prevent the revolution of said worm and to press said worm against said rack.

3. The combination with a lever, a rack and a wrench jaw fixed on said lever and a sliding jaw on said lever, of a worm engaging said rack and having a pintle revolubly mounted in said sliding jaw and having a rounded end, and a set screw having a co- 105

noidal point to engage said end to prevent the revolution of said worm and to force it against said rack.

4. The combination with a lever, a rack 5 and a wrench jaw fixed on said lever and a sliding jaw on said lever, of a worm engaging said rack and having a pintle revolubly

mounted in said sliding jaw, a set screw engaging said pintle to prevent the revolution of said worm and a spring engaging 10 said set screw to yieldingly hold same.

In testimony whereof, I affix my signature.

WALTER C. SHEPPARD.
